(57) **CLAIM**

The ornamental design for a fin shaped air heater, as shown and described.

DESCRIPTION

FIG. 1 is a perspective view from the top of the fin shaped air heater according to a first embodiment.

FIG. 2 is a front view of the fin shaped air heater according to the first embodiment.

FIG. 3 is a rear view of the fin shaped air heater according to the first embodiment.

FIG. 4 is a top view of the fin shaped air heater according to the first embodiment.

FIG. 5 is a bottom view of the fin shaped air heater according to the first embodiment.

FIG. 6 is a left side view of the fin shaped air heater according to the first embodiment.

FIG. 7 is a right side view of the fin shaped air heater according to the first embodiment.

FIG. 8 is a perspective view from the top of the fin shaped air heater according to a second embodiment.

FIG. 9 is a front view of the fin shaped air heater according to the second embodiment.

FIG. 10 is a rear view of the fin shaped air heater according to the second embodiment.

FIG. 11 is a top view of the fin shaped air heater according to the second embodiment.

FIG. 12 is a bottom view of the fin shaped air heater according to the second embodiment.

FIG. 13 is a left side view of the fin shaped air heater according to the second embodiment.

FIG. 14 is a right side view of the fin shaped air heater according to the second embodiment.

(Continued)

FIG. 15 is a perspective view from the top of the fin shaped air heater according to a third embodiment.
 FIG. 16 is a front view of the fin shaped air heater according to the third embodiment.
 FIG. 17 is a rear view of the fin shaped air heater according to the third embodiment.
 FIG. 18 is a top view of the fin shaped air heater according to the third embodiment.
 FIG. 19 is a bottom view of the fin shaped air heater according to the third embodiment.
 FIG. 20 is a left side view of the fin shaped air heater according to the third embodiment; and,
 FIG. 21 is a right side view of the fin shaped air heater according to the third embodiment.

1 Claim, 15 Drawing Sheets
